UNITED STATES PATENT OFFICE.

WALTER S. MCKEE, OF GLENCOE, ILLINOIS, AND PERCIVAL M. VILAS, OF MINNEAPOLIS, MINNESOTA, ASSIGNORS TO EDGAR ALLEN AMERICAN MANGANESE STEEL COMPANY, OF AUGUSTA, MAINE, A CORPORATION OF MAINE.

DIPPER FOR EXCAVATING-MACHINES.

1,069,889.

Specification of Letters Patent. Patented Aug. 12, 1913.

Application filed June 7, 1911. Serial No. 631,844.

To all whom it may concern:

Be it known that we, WALTER S. MCKEE, a citizen of the United States, and a resident of Glencoe, in the county of Cook and State of Illinois, and PERCIVAL M. VILAS, a citizen of the United States, and a resident of Minneapolis, in the county of Hennepin and State of Minnesota, have made and invented certain new and useful Improvements in Dippers for Excavating - Machines, of which the following is a specification.

Our invention relates to dippers or buckets for excavating, dredging and similar machines, and the objects thereof are to provide a dipper, the body portion of which is formed from two similar parts secured together to form a unitary dipper body, the said parts being of cast metal and, preferably, of cast manganese steel; to provide a dipper body of the type above referred to with a lip which, when in place, will assist in holding the two parts of the body portion together, whereby a stronger body portion is secured; to provide a scheme of riveting for securing the two parts together with a view to securing maximum strength at the joint between the two parts; to provide a construction and arrangement of ears to which the bail of the dipper is secured which will result in increased strength, and an arrangement in which the rivets which secure the ears to the body portion assist in securing the two parts of the body portion together; to provide certain improvements in and relating to the hinged bottom or door of the dipper; and to provide such other improvements in and relating to dippers or buckets for excavating, dredging and similar machines, as are hereinafter described, and illustrated in the accompanying drawings, and specifically claimed in the clauses of the concluding claim.

With the objects of invention above enumerated in view, our invention consists in the improved dipper shown in the drawings and hereinafter described and claimed, and in such modifications thereof as will be obvious to those skilled in the art to which our invention relates.

In the accompanying drawings: Figure 1 is a view partly in side elevation, and partly in section showing our improved dipper; Fig. 2 is a plan view of the same, a portion of the lip being broken away; Fig. 3 is a view

partly in front elevation and partly in section showing our improved dipper; Fig. 4 is a view showing a rear elevation of the dipper; Fig. 5 is a fragmentary view showing a detail; Fig. 6 is a fragmentary view showing a section upon a plane indicated by the line 6—6, Fig. 1, and, Fig. 7 is a fragmentary view taken upon a plane indicated by the line 7—7, Fig. 1, the lip of the dipper being omitted.

In the drawings, 8 is the front portion of our improved dipper, the same being curved on its front face as shown in Fig. 2 and having side portions extending to about the middle of the sides of the dipper body as shown by the dotted line 9, in Fig. 1, each of the two parts of which the dipper body is formed comprising about one-half of the body portion. The front part 8 is provided with upper and lower projecting ribs or bands 10, and with vertically extending ribs 11, for the purpose of strengthening the body portion, these ribs being formed integrally with the said front portion during the process of casting the same.

The rear portion of the body of our improved dipper is represented by the reference numeral 12, the rear face of the same being preferably somewhat curved and having forwardly extending sides as shown in Fig. 2, which sides and the rearwardly extending sides of the forward portion are secured together by means of a vertically extending series of rivets 13, as best shown in Fig. 1, to thereby form a unitary dipper body.

The joints between the abutting ends of the sides of the front and rear portions 8 and 12, are preferably formed as best shown in Figs. 1, 5, 6 and 7 wherein the side of the rear portion 12 is provided with an offset projecting flange 14 which extends over the sides of the front portion and vertically throughout the entire height of the dipper body, a vertically extending shoulder being thus formed along the line 9, Fig. 1, against which the extremities of the sides of the front portion 8 abut, thus to a considerable extent relieving the rivets 13 from shearing stresses as will be understood.

The rear portion 12 is provided with upper and lower ribs or bands 15 and with vertical and transverse ribs 16 upon the rear face thereof for the purpose of strengthen-

ing said rear portion and to provide lugs 17 whereby the bottom of the dipper is pivotally secured to the body portion, and other lugs 18 through which the mechanism for determining the angular position or inclination of the dipper with reference to the bank or surface to be dug away, is pivotally connected therewith. The rear portion with the features above enumerated is formed in 10 a single piece from cast metal as above explained in describing the front portion, manganese steel being the material preferably employed.

The dipper is lifted or moved in the act 15 of digging by means of a bail not shown, the lower ends of which are pivotally secured to the dipper body through ears 19 having an offset portion provided with a hole 20 at their free ends which lies opposite a hole 21 in the dipper body as shown in Fig. 7, a pin passing through these holes and a hole in the end of the bail as will be understood. These ears are arranged at an angle as shown 20 in Fig. 1, and a lug 22 is provided against 25 which the upper end of the ears abut and whereby the rivets whereby the ears are secured in place are relieved from shearing stresses. The ears are secured in place by a portion of the vertically arranged series of 30 rivets 13, the rivets which secure the ears in place passing also through the flange 14 of the rear portion 12 and the rear ends of the sides of the front portion 8 as best shown in Figs. 1 to 7.

35 The reference character 23 designates the lip portion of our improved dipper, the same being formed with a ledge or shoulder 24 which rests upon the upper edge of the body portion, and with a depending portion 25 which extends within the body portion of the dipper and is secured thereto by means of rivets 26, as many being provided as may be necessary. The length of the lip portion is such that it extends over the joint between 40 the front and rear portions of the dipper body, so that while most of the rivets 26 pass through the upper end of the forward portion 8 of the body, the rivets 26 near the ends of the lip pass through the upper end 45 of the rear portion whereby the lip contributes to the end of securing a strong connection between the front and rear portions of the dipper body. Some of the upper rivets of the series of rivets 13 besides passing through the flange 14 and front portion 50 8, pass also through the depending portion 25 of the lip, all as best shown in Figs. 1 and 3.

55 The reference characters 27 designate two supporting members pivotally connected with the rear portion of the dipper body by means of pins passing through the lugs 17 and which members support the swinging door or bottom 28 of the dipper. This door 60 is provided with ribs 29 upon its upper face,

and 30 is a sliding bolt located upon the lower face of the door and held in place by straps 31, and the free outer end of which bolt enters an opening 33 provided in the lower end of a stirrup 32 secured to the 70 lower portion of the front portion 8 of the body portion. The stirrup 32 is provided with a depending stop 34 which projects part way across the opening 33 so as to form a stop for the end of the bolt 30 while leaving the lower portion of the opening uncovered, so that dirt may not accumulate in the opening and interfere with the entry of the end of the bolt thereinto, all as best shown in Figs. 1 and 3.

80 The bolt 30 is operated to withdraw the end thereof from the opening 33 by means of a lever 35, pivotally connected therewith, one end of which lever is adjustably supported from a bracket 36 and the other end 85 of which is connected with an operating chain or cable, not shown.

85 37 are tapering ribs formed upon the inner surface of the front of the dipper body, and the reference numerals 38 designate 90 holes some being in the lip portion 23 and others extending through the vertically extending ribs 11 and the wall of the body portion upon which they are formed, the said holes being arranged in vertical rows 95 as shown.

Having thus described our invention, and explained the operation thereof, what we claim and desire to secure by Letters Patent is:

100 1. In a dipper for excavating, dredging and similar machines, a body portion comprising front and rear portions formed from cast metal and secured together along joints located in the sides of the body, one of said portions having a projecting flange portion and which flange portion overlies the end of the other of said body portions, and the end of which last-mentioned portion abuts against said shoulder; securing means extending through said flange portion for holding said two parts together; an ear by means of which a bail may be connected with said dipper body; and means for securing said ear to said body portion, said ear resting upon said flange portion, and the securing means for said ear extending through said flange portion and through the end of the second of said two parts.

110 2. In a dipper for excavating, dredging and similar machines, a body portion comprising front and rear portions formed from cast metal and secured together along vertically extending joints located in the sides of the body, one of said portions having a vertically extending shoulder and a projecting flange portion extending throughout the height of the body and which flange portion overlies the end of the other of said body portions, and the end of which last-men-

tioned portion abuts against said shoulder; securing means extending through said flange portion for holding said two parts together; an ear by means of which a bail 5 may be connected with said dipper body; and means for securing said ear to said body portion, said ear resting upon said flange portion and the securing means for said ear extending through said flange portion and 10 through the end of the second of said two parts.

3. In a dipper for excavating, dredging and similar machines, a body comprising front and rear portions formed from cast metal and secured together along vertically extending joints located in the sides of the body, one of said portions having a vertically extending shoulder and a projecting flange portion extending throughout the 20 height of the body, and which flange portion overlies the end of the other of said two portions, and the end of which last-mentioned portion abuts against said shoulder; securing means extending through said flange portion for holding said two parts together; an ear through which a bail may be connected with said dipper body; means for securing said ear to said body portion, said ear resting upon said flange portion and the 25 securing means for said ear extending therethrough and through the end of the second of said two parts; a lug adjacent the upper end of said flange portion and against which the upper end of said ear abuts; and 30 a detachable lip secured to the upper edge of the front portion of said body.

4. In a dipper for excavating, dredging and similar machines, a body made up of a front and a rear portion each formed in a 40 single piece from cast metal and each comprising substantially one-half of said body, said front and rear portions being secured together along joints located one in each side of the body between the front and rear faces 45 thereof to thereby form a two-part cast

metal dipper body; a plurality of lugs formed integrally with the rear portion of said body and located upon the rear face thereof; a lip secured to the upper edge of the front portion of said body and the rear 50 ends of which extend across the joint between said portions and terminate short of the rear surface of said rear portions; two lugs formed integrally with the rear portion of said body and located one upon each side 55 of said body adjacent the upper edge thereof; two ears inclined with reference to the longitudinal axis of said body and the upper ends of which abut against the lugs aforesaid and through which a bail may be connected with said body; and fastening means for securing said several parts together.

5. In a dipper for excavating, dredging and similar machines, a body portion; a swinging door secured thereto and extending across the bottom of said body portion; a sliding bolt carried by said door; a stirrup secured to said body portion and having an opening into which the end of said bolt may enter; and a stop extending from the upper 70 end of said opening downward and part way across said opening and against which the end of said bolt may rest, the lower portion of said opening being unobstructed by the stop aforesaid. 75
